UNITED STATES PATENT OFFICE

2,207,594

COMMUTATOR

Robert P. Loveland, Fort Wayne, Ind., assignor to
General Electric Company, a corporation of
New York

Application September 21, 1939, Serial No. 295,934

17 Claims. (Cl. 171—321)

My invention relates to commutators for dynamo-electric machines and methods of making the same.

An object of my invention is to provide improved and simplified commutator constructions.

Another object of my invention is to provide improved methods of making commutators.

Further objects and advantages of my invention will become apparent and my invention will be better understood from the following description referring to the accompanying drawing, and the features of novelty which characterize my invention will be pointed out with particularity in the claims annexed to and forming a part of this specification.

In the drawing, Fig. 1 is an end view of my improved commutator, partly broken away to illustrate the relative arrangement of the conducting and insulating portions thereof; Fig. 2 is a sectional side view taken along line 2—2 of Fig. 1; Fig. 3 is a side elevation of one of my improved commutator segments; Fig. 4 is a plan view of the commutator segment shown in Fig. 3; Fig. 5 is an end view of another embodiment of my invention, partly broken away to illustrate the relative arrangement of the conducting and insulating portions of the commutator; Fig. 6 is a side elevation of the commutator shown in Fig. 5 partly in section to illustrate the relative arrangement of the commutator segments with respect to the commutator support; Fig. 7 is a plan view of a sheet metal member from which the commutator segments of Fig. 5 are made; Fig. 8 is an end view of a modification of a sheet metal member, as shown in Fig. 7, having a heavier central segment portions; and Fig. 9 is a sectional side view of a further embodiment of my invention.

Referring to the drawing, I have shown in Figs. 1 and 2 a simplified commutator construction comprising a plurality of commutator segments 10 which are made from sheet metal punchings, as shown in Figs. 3 and 4. These sheet metal punchings are formed as strips including the central commutator segment portion 10 and end portions or prongs 11 on each end thereof. These prongs 11 are provided with anchoring heads 12 at the ends thereof and are punched in the form of a flat strip, as shown in Fig. 4, and then are bent at right angles to the central segment, portion 10, as shown in dashed line in Fig. 3. A plurality of these strips are assembled to form a complete commutator, and each strip is secured to a preformed annular insulating element 13 which may be made of any suitable ma-

terial such as hard fibre. The prongs 11 at each end of the segments 10 are clamped securely about the two outer edges of the annular insulating member 13 and a plurality of these segments are arranged in circumferentially spaced 5 apart relation about the outer peripheral surface of this insulating member. In order to provide a suitable support for the commutator and to insulate the commutator segments from the support, I provide a mass of moldable insulating 10 material 14, which may be made of any suitable material such as a phenolic condensation product, and mold this material about the inturned end portions or prongs 11 and between the inner sides of these prongs and a metal supporting 15 sleeve 15. In order further to insure the rigid support of the commutator upon the sleeve 15, I also mold the insulating material 14 around the outer ends of the prongs 11 and between the sleeve 15 and the insulating annular member or 20 sleeve 13. In forming this complete assembly, the moldable insulating material 14 may extend about the outer surface of the commutator segments 10, as shown by the dashed lines 16 in Figs. 1 and 2, and this excess insulating material 25 is then removed by turning or grinding the outer surface of the commutator to provide metallic outer contact surfaces to the commutator segments 10 which are concentric with respect to the mounting or supporting sleeve 15. Furthermore, the sleeve 15 may be omitted or removed, and the molded insulating portion 14 mounted directly upon a motor shaft.

In Figs. 5 and 6 I have shown a modification of my improved commutator construction which 35 provides a completed commutator very similar to that shown in Figs. 1 and 2. In manufacturing this commutator, a sheet metal blank of substantially rectangular shape is punched with a plurality of notches, slots, or indentations 17 on 40 each of two opposite parallel sides thereof. These slots 17 form a plurality of transversely extending prongs 18 separated by the slots 17, as shown in Fig. 7, and if desired, the prong portions 18 may be made of lesser thickness as compared to the 45 central or contact portion 24 to provide a heavier wearing bar section, as shown in Fig. 8. This sheet metal blank is formed into a substantially cylindrical shape about a preformed annular insulating sleeve member 19, which is arranged 50 adjacent the inner ends of the notches or slots 17, and the prongs 18 are firmly clamped about the outer ends of this insulating member. In order properly to support the commutator, I provide a metal mounting or supporting sleeve 29 55

which is arranged within the inturned end portions or prongs 18 and is secured thereto and insulated therefrom by a mass of moldable insulating material 21, formed of any suitable insulating material such as a phenolic condensation product. This insulating material 21 is molded about the inturned end portions or prongs 18 and between the inner ends of these prongs and under the insulating sleeve 19 to insulate completely the substantially cylindrical sheet metal element and the prongs 18 thereof from the supporting sleeve 20. The sleeve 20 is provided with a knurled or roughened surface 22 adjacent the central portion thereof about which the insulated material 20 is molded in order more firmly to secure it in position upon this supporting sleeve. After the insulating material 21 has been molded the outer peripheral surface of the commutator is turned down or ground to provide a peripheral metallic contact surface thereon which is concentric with the supporting sleeve 20. The original surface of the commutator is indicated by dashed lines 23 in Figs. 5 and 6. Individual commutator segments 24 are formed by extending the notches or slots 17 completely transversely across from side to side, so as to sever the cylindrical surface of the sheet metal member between each adjacent slot 17. This may be done conveniently by milling spacing grooves or slots 25 through the sheet metal member and partially into the annular insulating member 19. As in the arrangement shown in Figs. 1 and 2, this provides a commutator wherein the commutator segments are secured in position upon a preformed insulating sleeve and are mounted upon a supporting sleeve by another insulating member which secures the commutator segments in assembled relation about the first mentioned annular insulating member. If desired, however, the inner sleeve 20 may be omitted or removed and the insulating portion 21 mounted directly on a motor shaft.

In Fig. 9 I have shown a further modification of my improved commutator construction, wherein in a plurality of commutator segments 26 are arranged in spaced apart relation about the outer peripheral surface of a preformed annular insulating sleeve member 27. Each of these segments 26 is provided with end portions or prongs 28 at both ends thereof clamped about the end portions of an insulating sleeve 27. A second insulating sleeve or bushing 29 is arranged in contact with the inner surface of the prongs 28 and provides a press fit between the prongs 28 and the sleeve 29 in order to secure the segments in assembled relation about the sleeve 27. The insulating sleeve 29 also may be provided with a radially extending collar 30 which engages a portion of the ends of prongs 28 on one end of the commutator. This sleeve 29 is formed of any suitable insulating material such as a phenolic condensation product or a fibre sleeve which is securely mounted upon a metal supporting sleeve member 31. In order to insure the concentricity of this commutator, the outer peripheral contact surface thereof is turned or ground down from its original size, as indicated by dashed line 32, to the size shown in full lines in this figure. This commutator construction provides substantially the same completed structure as that shown in the other figures, and the commutator segments may be made as separate punchings as in Figs. 1 to 4 or as a sheet metal stamping and subsequently cut apart as in Figs. 5 to 75. 8. In addition, it is cheaper to manufacture, as

it does not require the molding of the mounting insulating member between the supporting sleeve and the inner side of the inturned prongs 28. As in the other constructions, the inner sleeve 31 may be omitted if desired.

While I have illustrated and described particular embodiments of my invention, modifications thereof will occur to those skilled in the art. I desire it to be understood, therefore, that my invention is not to be limited to the arrangements disclosed, and I intend in the appended claims, to cover all modifications which do not depart from the spirit and scope of my invention.

What I claim as new and desire to secure by Letters Patent of the United States is:

1. A commutator including a preformed annular insulating element, a plurality of commutator segments arranged in circumferentially spaced apart relation about the periphery of said annular element, each of said segments having an inturned portion securely clamped about a portion of said insulating element, and means including a second insulating element arranged in contact with a surface of said inturned segment portions for retaining them in assembled relation.

2. A commutator including a preformed annular insulating element, a plurality of commutator segments arranged in circumferentially spaced apart relation about the periphery of said annular element, each of said segments having an inturned portion securely clamped about a portion of said insulating element, means including a second insulating element arranged in contact with a surface of said inturned segment portions for retaining them in assembled relation, and a supporting sleeve secured within said second insulating element.

3. A commutator including a preformed annular insulating element, a plurality of commutator segments arranged in circumferentially spaced apart relation about the periphery of said annular element, each of said segments having an inturned portion of lesser thickness than the remainder of said segments arranged in securely clamped relation about a portion of said insulating element, and means including a second insulating element arranged in contact with a surface of said inturned segment portions for retaining them in assembled relation.

4. A commutator including a preformed annular insulating element, a plurality of commutator segments arranged in circumferentially spaced apart relation about the periphery of said annular element, each of said segments having an inturned portion securely clamped about a portion of said insulating element, and moldable insulating material arranged about a part of said inturned portions of said segments.

5. A commutator including a preformed annular insulating element, a plurality of commutator segments arranged in circumferentially spaced apart relation about the periphery of said annular element, each of said segments having an inturned portion securely clamped about a portion of said insulating element, a moldable insulating material arranged about a part of said inturned portions of said segments, and a supporting sleeve secured within said moldable insulating material.

6. A commutator including a preformed annular insulating element, a plurality of commutator segments arranged in circumferentially spaced apart relation about the periphery of said

annular element, each of said segments having an inturned portion securely clamped about a portion of said insulating element, and means including an insulating sleeve arranged in contact with a surface of said inturned segment portions for retaining them in assembled relation.

7. The method of making a commutator which comprises arranging an electrically conductive member about the outer peripheral surface of an annular insulating element, clamping an end of the conductive member about a part of the annular insulating element, and placing another insulating element in contact with a part of the clamped end portion of the electrically conductive member to retain it in assembled relation.

8. The method of making a commutator which comprises arranging an electrically conductive member about the outer peripheral surface of an annular insulating element, clamping an end of the conductive member about a part of the annular insulating element, placing another insulating element in contact with a part of the clamped end portion of the electrically conductive member to retain it in assembled relation, and arranging a supporting sleeve within said last-mentioned insulating element.

9. The method of making a commutator which comprises forming a plurality of strips of electrically conductive material, arranging the strips of conductive material in spaced apart relation about the outer peripheral surface of an annular insulating element and forming inturned portions adjacent an end of each strip in clamped engagement about a part of the annular insulating element, and placing another insulating element in contact with the inner sides of the inturned portions of the strips to retain them in assembled relation.

10. The method of making a commutator which comprises forming a plurality of strips of electrically conductive material, arranging the strips of conductive material in spaced apart relation about the outer peripheral surface of an annular insulating element and forming inturned portions adjacent an end of each strip in clamped engagement about a part of the annular insulating element, and placing a moldable insulating material about a part of the inturned portions of the strips.

50 11. The method of making a commutator which comprises forming a plurality of strips of electrically conductive material, arranging the strips of conductive material in spaced apart relation about the outer peripheral surface of an annular insulating element, clamping each end of each strip about a part of the annular insulating element, and placing a moldable insulating material about a part of the inturned portions of these strips.

60 12. The method of making a commutator which comprises forming a plurality of strips of an electrically conductive material, arranging the strips of conductive material in spaced apart relation about the outer peripheral surface of an annular insulating element, clamping an end of each strip about a part of the annular insulating element, and placing a moldable insulating material about a part of the inturned portions of the

strips and between the inner surface thereof and a supporting sleeve.

13. The method of making a commutator which comprises forming a plurality of notches along an edge of a sheet metal member to provide a plurality of transversely extending prongs separated by these notches, arranging the prongs in clamping engagement about an edge of an annular insulating element, placing another insulating element in contact with the inner sides of the prongs to retain them in position, and extending the notches transversely of the sheet metal member to sever it into a plurality of separated segments.

14. The method of making a commutator which comprises forming a plurality of notches along two opposite parallel edges of a sheet metal member to provide a plurality of transversely extending prongs on each respective edge thereof separated by the notches, clamping the prongs along each edge of the metal member about an edge of an annular insulating element, placing another insulating element in contact with the inner sides of the prongs to retain them in position, and extending the notches transversely of the sheet metal member to sever it into a plurality of separated segments.

15. The method of making a commutator which comprises forming a plurality of notches along an edge of a sheet metal member to provide a plurality of transversely extending prongs separated by the notches, forming a substantially cylindrical element of the sheet metal member, arranging an annular insulating element within the cylindrical member, arranging the prongs of the cylindrical member in clamping engagement about an edge of the annular insulating element, extending the notches in the cylindrical element to completely sever it into a plurality of segments, and placing another insulating element in contact with the inner sides of the prongs to retain the segments in assembled relation.

16. The method of making a commutator which comprises forming a plurality of notches along two opposite parallel edges of a sheet metal member to provide a plurality of transversely extending prongs on each edge separated by the notches, clamping the prongs along each edge of the sheet metal member about an edge of an annular insulating element, placing a moldable insulating material about the prongs to retain the sheet metal member in position and also between the inner surface of the prongs and a supporting sleeve, and extending the notches in the sheet metal member to sever it into a plurality of segments.

17. The method of making a commutator which comprises forming a plurality of notches along two opposite parallel edges of a sheet metal member to provide a plurality of transversely extending prongs on each edge separated by the notches, clamping the prongs along each edge of the sheet metal member about an edge of an annular insulating element, placing a moldable insulating material about the prongs to retain the sheet metal member in position, and extending the notches in the sheet metal member to sever it into a plurality of segments.

ROBERT P. LOVELAND.
